United States Patent Office

Des. 180,587
Patented July 9, 1957

180,587

CREAMER

Alfred Dube, Lincoln, Ill., assignor to Stetson China Co., Inc., Lincoln, Ill., a corporation of Illinois

Original application December 13, 1955, Serial No. D. 39,315, now Design Patent No. 179,797, dated March 5, 1957. Divided and this application November 20, 1956, Serial No. 43,856

Term of patent 14 years

(Cl. D44—21)

Fig. 1

The present application is a division of my co-pending application Serial No. D. 39,315, filed December 13, 1955, now Patent D. 179,797.

I claim:

The ornamental design for a creamer, as shown.
